TEST TUBE BRUSHES

Edwin G. Weichselbaum, Florissant, Mo., assignor, by
mesne assignments, to Brunswick Corporation, Chi-
cago, Ill., a corporation of Delaware
Filed Mar. 13, 1961, Ser. No. 95,321
6 Claims. (Cl. 15—164)

This invention relates to certain new and useful im-
provements in cleaning implements for the interior of 10
laboratory glassware and, more particularly, to a test
tube brush.

For many years, the only type of cleaning implement
available for cleaning the insides of test tubes, and similar
types of laboratory glassware, has been a brush consisting
of a long twisted wire handle having a plurality of diam-
etrically projecting tufts of hair-bristles for a substantial
portion of its length adjacent one end. Such brushes,
however, have never been capable of scrubbing free any-
thing but the most superficial stains and adherent solid
materials from the interior surfaces of a test tube or other
piece of laboratory glassware. In fact, it has been com-
mon practice to clean laboratory glassware by the use of a
dichromate cleaning solution, or some other rather strong
corrosive detergent which is poured into the piece of
laboratory glassware and allowed to remain for a period of
time, after which the cleaning solution is poured back into
the original container for re-use until its strength is greatly
diminished or exhausted. The piece of laboratory glass-
ware which has thus been soaked is then rinsed out and
finally cleaned with a conventional test tube brush. Not
only is this procedure a very time consuming and costly
one, but produces characteristic stains on the hands of
the laboratory technician and, in many cases, does not
effectively clean the laboratory glassware, even after pro-
longed periods of chemical soaking.

Moreover, the hair-bristles of conventional test tube
brushes are not particularly durable, even when used only
with ordinary tap water but, when subjected to the cor-
rosive action of the residual quantities of so-called "clean-
ing solutions," the rinsing and scrubbing operations will de-
teriorate the hair-bristles of the brush rapidly. Conse-
quently, a conventional test tube brush soon wears out and
must be discarded. Another difficulty with conventional
test tube brushes is the fact that the bristles near the end
become worn or at least deformed very early in the
life of the test tube brush, thereby exposing the wire
end which rubs against the bottom of the test tube pro-
ducing scarring and scratching which seriously impairs
the test tube itself. In fact, for many laboratory tech-
niques wherein visual inspection of the contents is neces-
sary, a test tube which has been washed several times
with a conventional test tube brush will become so
seriously scarred as to be rendered virtually useless.

It is, therefore, the primary object of the present in-
vention to provide a test tube brush which is extremely
durable, easily sterilized, and can be produced at relatively
low cost.

It is another object of the present invention to provide a
test tube brush of the type stated which is formed as a
single unitary or "one-piece" structure which is strong
and possesses extremely efficient scrubbing properties.

It is a further object of the present invention to provide
a test tube brush having a uniquely arranged combination
of radial scrubbing fingers and intermediate scraping
blades formed of a resilient material so that the device
will readily accommodate itself to the contours of the
surface being cleaned and may be conveniently inserted into
and removed from laboratory vessels of various types and
shapes.

With the above and other objects in view, my invention

2

resides in the novel features of form, construction, arrange-
ment, and combination of parts presently described and
pointed out in the claims.

In the drawings (one sheet):

5 FIG. 1 is a front elevational view of a test tube brush
constructed in accordance with and embodying the pres-
ent invention;

FIGS. 2, 3, and 4, are sectional views taken along lines
2—2, 3—3, and 4—4, respectively, of FIG. 1;

FIG. 5 is a fragmentary front elevational view of a
modified form of a test tube brush constructed in accord-
ance with and embodying the present invention; and

FIG. 6 is a transverse sectional view taken along line
6—6 of FIG. 5.

15 Referring now in more detail and by reference char-
acters to the drawings which illustrate practical embodi-
ments of the present invention, A designates a test tube
brush which is moulded or otherwise suitably formed as
a unitary or "one-piece" structure, from a synthetic resin,
such as polyethylene, polypropylene, polyvinyl acetate or
similar resilient rubber-like material, and comprises an
elongated rod-like handle 1 provided along its length with
a plurality of uniformly spaced axial corrugations or
beads 2. At its distal end, the handle 1 is integrally
25 provided with an enlarged knob 3 having a diametrically ex-
tending aperture 4 by which the test tube brush A may be
hung from a suitable pin or hook in the usual manner.

At its proximal end, the handle 1 is slightly reduced in
cross-sectional size to form a stem-portion 5 which is
30 integrally provided around its periphery with a plurality
of axially extending series of radially projecting tines 6
and a pair of diametrically opposed solid flat blade mem-
bers 7 which extend axially along the stem 5 and are some-
what greater in width than the radial length of the tines
35 6, the rows of tines 6 and the blades 7 being symmetrical-
ly arranged as shown in FIG. 3.

The two diametrically opposed blades 7 are, moreover,
slightly greater in axial length than the stem 5 and are
unitarily connected across the bottom of the stem 5 in an
40 arcuate bottom web 8. Finally, the blades 7 are preferably
curved or rounded at their upper margins in the provision
of arcuate top-edges 9, all as best seen in FIG. 1.

45 As will be seen by reference to FIG. 4, the tines or
scrubbing-fingers 6 in each axial row are uniformly spaced
along the length of the stem 5 so as to exert individual
50 bristle-like cleansing action against the interior surface
of the test tube or other piece of laboratory glassware be-
ing scrubbed. However, each individual tine or scrubbing-
finger 6 is integrally joined to the stem 5 and is in itself
sufficiently flexible so that it is not readily pulled loose, de-
formed, or otherwise impaired during use.

55 The test tube brush A, being made of resilient material,
may be readily inserted into a test tube or into the
narrowed neck of some other piece of laboratory glass-
ware, and both rotated and reciprocated therein to achieve
a highly efficient cleansing action. Inasmuch as the test
60 tube brush A is made of a water-resistant and chemical-
resistant synthetic resin, it will not readily become water-
logged and will not deteriorate in the presence of cor-
rosive cleaning agents. In fact, the test tube brush A has
been found, as a matter of actual practice, to be so effi-
cient in its mechanical cleaning action that strong or cor-
rosive chemical cleaning solutions becomes unnecessary in
65 most cases.

66 It is also possible to provide a modified form of test
tube brush A', as shown in FIG. 5 which also comprises
an elongated rod-like handle 1' having axial corruga-
tions or ribs 2' and a knob 3', substantially similar to,
but somewhat larger in size than the previously described
70 test tube brush A. The form of test tube brush A' is
designed for use with large sized laboratory glassware

and particularly test tubes of large internal diametral size. Accordingly, the handle 1' is integrally provided at its proximal end with a diametrically enlarged head-member 10 which is internally cored out from the bottom in substantially tubular form and is integrally provided upon its external surface with a plurality of rows of tines or scrubbing-fingers 6' and radially projecting diametrically opposed blades 7' substantially similar to the previously described tines or scrubbing-fingers 6 and blades 7. The blades 7', however, are not quite as long in axial dimension as the head-member 10, but are rounded off at the upper and lower corner-margins as at 9'. It will, of course, be understood that the tines or scrubbing-fingers 6' and blades 7' are slightly heavier in cross-section than the previously described tines or scrubbing-fingers 6 and blades 7, inasmuch as the test tube brush A' is intended for use with larger test tubes and other laboratory vessels.

It should be understood that changes and modifications in the form, construction, arrangement, and combination of the several parts of the test tube brushes may be made and substituted for those herein shown and described without departing from the nature and principle of my invention.

Having thus described my invention, what I claim and desire to secure by Letters Patent is:

1. A cleaning implement formed as a unitary one-piece structure from a synthetic resin of somewhat rubber-like resilient consistency, said structure integrally comprising an elongated rod-like handle provided at one end with an axially extending stem portion, a plurality of rows of radially projecting tines formed integrally upon the outer face of the stem, said rows being arranged symmetrically around the stem, the tines in each row being axially spaced in such a manner that each tine in one row is co-planar with a corresponding tine in each of the other rows thereby forming a circularly arranged group of tines, the tines in each such group being of substantially the same radial length so that their outer ends are substantially equidistant from the longitudinal center-line of the stem portion, and a pair of diametrically opposed radial blades interposed between equal groups of rows, said blades being radially wider at all points along its axial length than the radial length of the adjacent groups of tines.

2. A cleaning implement formed as a unitary one-piece structure from a synthetic resin of somewhat rubber-like resilient consistency, said structure integrally comprising an elongated rod-like handle provided at one end with an axially extending stem portion, a plurality of rows of radially projecting tines formed integrally upon the outer face of the stem, said rows being arranged symmetrically around the stem, the tines in each row being axially spaced in such a manner that each tine in one row is co-planar with a corresponding tine in each of the other rows thereby forming a circularly arranged group of tines, the tines in each such group being of substantially the same radial length so that their outer ends are substantially equidistant from the longitudinal center-line of the stem portion, and a pair of diametrically opposed radial blades interposed between equal groups of rows, said blades being radially wider at all points along its axial length than the radial length of the adjacent groups of tines and being slightly greater in axial length than the stem.

3. A cleaning implement formed as a unitary one-piece structure from a synthetic resin of somewhat rubber-like resilient consistency, said structure integrally comprising an elongated rod-like handle, provided at one end with an axially extending stem portion, a plurality of rows of radially projecting tines formed integrally upon the outer face of the stem, said rows being arranged symmetrically around the stem, the tines in each row being axially spaced in such a manner that each tine in one row is co-planar with a corresponding tine in each of the other rows thereby forming a circularly arranged group of tines, the tines in each such group being of substantially the same radial length so that their outer ends are sub-

stantially equidistant from the longitudinal center-line of the stem portion, and a pair of diametrically opposed radial blades interposed between equal groups of rows, said blades being radially wider at all points along its axial length than the radial length of the adjacent groups of tines and being slightly greater in axial length than the stem, said blades also being unitarily connected across the bottom of the stem in an arcuate bottom web which is curved upwardly at its outer margins.

4. A cleaning implement formed as a unitary one-piece structure from a synthetic resin of somewhat rubber-like resilient consistency, said structure integrally comprising an elongated rod-like handle provided at one end with an axially extending downwardly opening tubular stem portion, a plurality of rows of radially projecting tines formed integrally upon the outer face of the stem, said rows being arranged symmetrically around the stem, the tines in each row being axially spaced in such a manner that each tine in one row is co-planar with a corresponding tine in each of the other rows thereby forming a circularly arranged group of tines, the tines in each such group being of substantially the same radial length so that their outer ends are substantially equidistant from the longitudinal center-line of the stem portion, and a pair of diametrically opposed radial blades interposed between equal groups of rows, said blades being radially wider at all points along its axial length than the radial length of the adjacent groups of tines and being slightly greater in axial length than the stem.

5. A cleaning implement formed as a unitary one-piece structure from a synthetic resin of somewhat rubber-like resilient consistency, said structure integrally comprising an elongated rod-like handle provided at one end with an axially extending stem portion, a plurality of rows of radially projecting tines formed integrally from the outer face of the stem, said rows being arranged symmetrically around the stem, the tines in each row being axially spaced in such a manner that each tine in one row is co-planar with a corresponding tine in each of the other rows thereby forming a circularly arranged group of tines, the tines in each such group being of substantially the same radial length so that their outer ends are substantially equidistant from the longitudinal center-line of the stem portion, and a pair of diametrically opposed radial blades interposed between equal groups of rows, said blades being radially wider at all points along its axial length than the radial length of the adjacent groups of tines and being slightly greater in axial length than the stem.

6. A cleaning implement formed as a unitary one-piece structure from a synthetic resin of somewhat rubber-like resilient consistency, said structure integrally comprising an elongated rod-like handle provided at one end with an axially extending stem portion, a pair of diametrically opposed radial blades integrally formed with said stem and extending outwardly therefrom, each of said blades having a pair of opposed flat faces, a plurality of rows of radially projecting tines formed on the outer face of said stem and being annularly spaced between the flat face of one blade and the flat face of the other blade, said stem also being provided with a plurality of rows of radially projecting tines formed on the outer face of said stem and being annularly spaced between the other flat surfaces of each of said blades, the tines in each row being axially spaced in such a manner that each tine in one row is co-planar with a corresponding tine in each of the other rows thereby forming a circularly arranged group of tines, the tines in each such group being of substantially the same radial length so that their outer ends are substantially equidistant from the longitudinal center-line of the stem portion, said blades being radially wider

at all points along its axial length than the radial length of the adjacent groups of tines and being slightly greater in axial length than the stem, said blades also being unitarily connected across the bottom of the stem in an arcuate bottom web which is curved upwardly at its outer margins.
